US00D994647S

(12) **United States Design Patent** (10) **Patent No.:** **US D994,647 S**
Rothman et al. (45) **Date of Patent:** **** Aug. 8, 2023**

(54) **MICROPHONE**

(71) Applicants: **Samuel Rothman**, Monterey Park, CA (US); **Charlene Amelia Gibbs**, Monterey Park, CA (US)

(72) Inventors: **Samuel Rothman**, Monterey Park, CA (US); **Charlene Amelia Gibbs**, Monterey Park, CA (US)

(73) Assignee: **Ohma World 2 Inc.**, Monterey Park, CA (US)

(**) Term: **15 Years**

(21) Appl. No.: **29/806,042**

(22) Filed: **Aug. 31, 2021**

(51) LOC (14) Cl. **14-01**

(52) U.S. Cl.

USPC **D14/225**

(57) **CLAIM**

The ornamental design for a microphone, as shown and described.

DESCRIPTION

FIG. 1 is a front perspective view of a microphone showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the microphone that form no part of the claimed design.

1 Claim, 4 Drawing Sheets
